Primary Examiner — Elizabeth J Oswecki(74) *Attorney, Agent, or Firm* — Hunton & Williams LLP(57) **CLAIM**

We claim the ornamental design for a financial transaction machine, as shown and described.

DESCRIPTION

FIG. 1 is a front perspective view of a financial transaction machine showing our new design;

FIG. 2 is a front elevation view of FIG. 1;

FIG. 3 is a back elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1; and,

FIG. 8 is a rear perspective view of FIG. 1.

The broken lines in the drawings illustrate environmental structure on the article and form no part of the claimed design.
